UNITED STATES PATENT OFFICE.

CHARLES C. STEVENS, OF SAGINAW, MICHIGAN.

RAKE.

1,133,676.

Specification of Letters Patent. Patented Mar. 30, 1915.

Application filed February 9, 1914. Serial No. 817,553.

To all whom it may concern:

Be it known that I, CHARLES C. STEVENS, a citizen of the United States, residing at Saginaw, in the county of Saginaw and 5 State of Michigan, have invented certain new and useful Improvements in Rakes; and I do hereby declare the following to be a full, clear, and exact description of the invention, such as will enable others skilled in 10 the art to which it appertains to make and use the same.

My invention relates to improvements in rakes, in which a cleaner operates in conjunction with the rake-teeth.

15 The objects of my improvement are, first, to suspend the cleaner from a point sufficiently high above the center of gravity of the cleaner to allow the cleaner to swing with considerable momentum, like a pendulum, back-and-forth between the rake-teeth; second, to provide a support for the cleaner that will reduce the friction and permit the cleaner to swing freely without binding; third, to provide a cleaning device which 25 will prove efficient, simple in construction and inexpensive to manufacture. I attain these objects by the devices illustrated in the accompanying drawings, described and claimed and the equivalents thereof.

30 Referring to the drawings, Figure 1 is a plan view of my improved rake. Fig. 2 is a view, partly in section, taken on line 2—2 of Fig. 1. Fig. 3 is a fragmentary view, in perspective, showing the manner of suspending the cleaner. Fig. 4 is a similar view showing the opposite side of the suspending device.

Referring to the drawings, 1 designates the rake-head, 2 the teeth carried thereby 40 and 3 the handle connected to the rake-head. These parts comprise the parts of the usual rake.

44 4 designates a pair of brackets or brace-bars secured to the handle 3 in any suitable 45 manner, as with the fastening device 5. These brace-bars are each provided with a foot 6 which is suitably secured to the rake-head 1, giving rigidity thereto. The feet 6, it will be observed, extend laterally to the 50 ends of the rake-head and are then bent to project outwardly from the feet to form a supporting lug 7 at each end of the rake-head. These lugs are each provided with a suitable opening 8.

55 Suspended by its ends from the lugs 7 is a rake-tooth cleaner comprising a head-bar

9 having the teeth 10 adapted to swing between the rake-teeth 2 to keep them clean and free from accumulation of grass, leaves and the like. The cleaner is suspended from 60 laterally projecting spindles 11 loosely received in the openings of the lugs 7. These spindles are preferably arranged somewhat higher than the head-bar 9 of the cleaner, as shown to allow the head-bar to swing 65 freely underneath the handle and brace-bars. The spindles 8 are preferably triangular in cross-section so as to provide substantially knife-edge support, thereby reducing friction and permitting the cleaner to swing 70 easily, like a pendulum, since the suspension or pivot point of the cleaner is considerably higher than the center of gravity of the cleaner.

By suspending the cleaner from its ends 75 substantially as illustrated, any ordinary degree of bending or warping of the cleaner will not cause it to bind at the supporting bearings, as would be the case if the head-bar 9 were pivoted at some point intermediate 80 at its ends.

Having thus described my invention, what I claim and desire to secure by Letters Patent is:

1. In a rake of the class described, the 85 combination with a rake-head and handle connected thereto, of a rake-tooth cleaner pivotally suspended, at its ends only, and adapted to swing freely from said rake-head, said cleaner comprising a horizontally-disposed head-bar having downwardly-extending teeth thereon, the points of suspension of said cleaner being above the head-bar.

2. In combination with a rake-head and 95 handle connected thereto, a pair of brace-members secured at one end to said handle and at their opposite ends to said rake-head, a supporting lug formed with an opening and projecting from each of said brace-members 100 adjacent the ends of the rake-head and substantially at right-angles thereto, and a rake-tooth cleaner hingedly supported, at its ends only, upon said lugs.

3. In a rake, the combination of a rake- 105 head having a pair of projecting lugs arranged at the ends thereof, a rake-tooth cleaner comprising a horizontally-disposed head-bar formed with downwardly-extending teeth and having laterally projecting 110 spindles arranged above said head-bar, said spindles loosely received in said lugs for

hingedly suspending said cleaner from the ends of the rake-head, to permit free oscillation of said cleaner when the rake is operated.

- 5 4. The combination with a rake-head and handle, of a pair of brace-bars extending from the handle to the rake-head and bent at their ends to form lugs adjacent the ends of the rake-head, a tooth-cleaner comprising a head-bar having teeth and having laterally projecting spindles at its ends, said spindles being located higher than the head-bar of the cleaner and adapted to be loosely received in the openings of said lugs, the 10 teeth of said cleaner adapted to project between the teeth of the rake-head.
- 15 5. A rake-cleaner comprising a horizontally disposed head-bar provided with downwardly extending teeth and having laterally projected V-shaped spindles arranged 20

at a point higher than the head-bar of the cleaner, substantially as shown and for the purpose specified.

6. In a rake, the combination of a rake-head having a pair of projecting lugs arranged at the ends thereof, a rake-tooth cleaner comprising a horizontally disposed head-bar extending across said rake-head from side to side formed with teeth and having laterally projecting V-shaped spindles, 25 30 said spindles loosely received in said lugs for hingedly suspending said cleaner from the ends of the rake-head.

In testimony whereof, I affix my signature in presence of two witnesses.

CHARLES C. STEVENS.
